UNITED STATES PATENT OFFICE.

WILBUR C. LAMBERT, OF NEW HAVEN, CONNECTICUT.

MACHINE FOR GRINDING CUTLERY.

SPECIFICATION forming part of Letters Patent No. 601,443, dated March 29, 1898.

Application filed February 8, 1896. Serial No. 578,470. (No model.)

To all whom it may concern:

Be it known that I, WILBUR C. LAMBERT, a citizen of the United States, residing at New Haven, county of New Haven, and State of Connecticut, have invented a new and useful Improvement in Machines for Grinding Cutlery, of which the following is a specification, reference being had to the accompanying drawings, forming part thereof.

My invention relates to edge-tool-grinding machinery, and has especial reference to machines for grinding articles of cutlery, such as knife-blades, razors, &c.; and it has for its object to materially increase the working capacity of such machines and at the same time improve the character of the work done thereby.

To this end my invention consists in the grinding-machine constructed and operating as hereinafter fully described, and particularly pointed out in the claims.

Referring to the drawings, in which like numerals designate like parts in the several views, Figure 1 is a plan view of a grinding-machine embodying my invention. Fig. 2 is a front elevation thereof. Fig. 3 is a rear elevation thereof. Fig. 4 is an end view with a portion of the bed cut away at the line $x-x$ of Fig. 3. Fig. 5 is a plan view, drawn to a larger scale, of the mechanism located at one end of the machine. Fig. 6 is a partial cross-section thereof, taken at line $y-y$ of Fig. 5. Fig. 7 is a cross-section taken at line $z-z$ of Fig. 5. Fig. 8 is a detail view of the means for adjusting the work-supporting tables toward and away from the abrading-wheels. Fig. 9 is a vertical section of the bearings for the wheel-chucks and their shaft. Fig. 10 is a detail view of the eccentric-engaging arm which vibrates the work being ground. Fig. 11 is a partial longitudinal section thereof, taken on line $w-w$ of Fig. 12. Fig. 12 is a plan view of said arm. Fig. 13 is a longitudinal section of one of the work-clamping devices. Fig. 14 shows the cam-hub thereof detached. Fig. 15 is a partial view of the clamp-operating lever. Fig. 16 is a partial longitudinal section of the reversing-lever for one of the work-carriages and the means for locking it in one of its positions. Fig. 17 is a vertical section taken at line $v-v$ of Fig. 16. Fig. 18 is a longitudinal section of a portion

of the driving-shaft for the work-carriages, showing the reversing-gears and their sliding sleeve. Fig. 19 is a face view of one of the die-holders for the work. Fig. 20 is a view in perspective of one of the dies. Fig. 21 is a horizontal section showing the base of one of the work-carriages, the way upon which it moves, and the forming depression therein which causes the abrading-wheel to form the beveling-point of the blade. Figs. 22 and 23 are respectively a face view and a plan view of a portion of said way, having inserted therein an independent plate containing the forming or shaping recess. Figs. 24, 25, and 26 are respectively a face view, a plan, and an end view of still another modification in which the shaping-recess is located in an adjustable plate mounted on the way.

The numeral 1 designates the supporting-base of the machine, which will be provided with suitable legs or feet, as shown, and has its interior formed into a tank or reservoir for holding water, as is customary in grinding machinery of this character. Said base supports the bed 2 of the machine, which bed at the two ends of the machine is enlarged in area to form two shallow pans or receptacles for receiving the water fed to the abrading-wheels, as shown in Figs. 1, 2, and 3, and said pans communicate with the reservoir in the base by passages 3 (see Fig. 9) to permit the water to return to the latter after being used in a well-known manner. At the center of the machine the bed 2 supports the standards 4, in which are located the bearings for the shaft 5, which carries the chucks 6 for the annular abrading-wheels 7. I prefer to form the bearings for said shaft 5 as shown in Fig. 9—that is to say, by providing two hubs 8, which are seated in the standards 4 and are provided internally with suitable antifriction-linings, as shown, Babbitt metal being preferably used, and are provided at their adjacent ends with similar annular bearing-surfaces 9. The shaft 5 passes through said hubs, and between the latter it carries the band-pulley 10, by which motion is transmitted to the machine by belt from a power-shaft, said pulley having formed integral therewith the smaller pulley 12 to receive the belt by which the motion of shaft 5 is transmitted to the driving-shaft for the work-carriages, as will be presently described.

One end of the hub of said band-pulleys bears against the annular bearing-ring 9 of one of the hubs 8, and its opposite end is threaded to receive the nut 13 and lock-nut 14, which 5 latter bears against the bearing-ring of the opposite hub 8. Provision is thus made for causing the end thrust of shaft 5 in both directions to be taken by the bearing-rings on said hubs and for compensating for wear of said rings 10 by the adjustment afforded by the two nuts 13 14, so that a perfectly true and steady movement of said shaft and the abrading-wheels carried thereby is assured at all times.

15 The abrading-wheels 7, carried at the ends of the shaft 5, form right and left hand wheels, and upon the bed of the machine at each end of the latter are located the carriages for the work and their operating mechanisms. Said mechanisms are exact duplicates of each 20 other, and the various parts thereof are designated by the same numerals; but to avoid prolixity I will describe the construction and operation of the mechanism at one end of the machine merely, it being understood that such 25 description applies equally well to either of said duplicate mechanisms.

Upon the bed of the machine is located a dovetail way 15, (see Fig. 4,) extending in a direction parallel with the axis of shaft 5 and perpendicular to the face of the abrading-wheel, upon which way is mounted a table 16, which supports the work-carriage and its operating mechanism. Screw-bolts 17, passing through the overlapping edge of said table against an interposed gib, (see Figs. 4 and 6,) serve to securely fasten it against movement; but by loosening said screws the table is rendered free to have a limited movement toward and away from the face of the abrading-wheel, which movement is imparted to it by means of a screw-rod 18, revolvably supported at the outer end of the bed, said rod carrying a hand-wheel at its outer end and engaging at its inner end a nut 19 on the table, as shown in Figs. 4 and 6, the way 15 being longitudinally recessed to receive said rod and nut. Upon said table 16 is located a way 20, extending at a right angle to the way 15 and parallel with the face of the abrading-wheel, upon which is mounted the work-carriage 21. Motion is imparted to said carriage by a screw-shaft 22, supported in bearings on table 16, said shaft engaging a nut 23, connected to the carriage by a swivel-bolt (see Fig. 8) to permit a slight tilting movement of the carriage horizontally, for a purpose which will presently appear. Said shaft 22 carries at one end the spur-gear 24, and preferably has its opposite end reduced and fitted to receive a wrench, as shown in Figs. 5 and 7, to permit the shaft to be operated manually in adjusting the starting-point of the traverse of the carriage. Said gear 24 on the shaft meshes with a spur-gear 25, carried by a plate 26, which is dovetailed into an angle-bar 27, bolted to the under side of the bed, (see Fig. 7,) screw-bolts 28 passing through slots in

said angle-bar into said plate, (see Fig. 2,) serving to securely hold the latter in position, while permitting it to have a limited adjustment longitudinally of the machine. The object of such provision for adjustment of plate 26 is to enable the gear 25 to be maintained in its proper working position relatively to gear 24 when the latter is shifted with the adjustment of table 16, before mentioned. Rigidly secured to said gear 25 is a bevel-gear 29, which is adapted to be engaged alternately by two oppositely-faced bevel-gears 30 31, carried by a sleeve 32, which has a splined connection with the driving-shaft 33, (see Fig. 18,) whereby longitudinal movement of said sleeve to throw either of its gears into mesh with gear 29 is permitted. Said shaft 33 is supported in suitable bearings upon the plates 26 at the rear side of the machine and carries midway between its ends the spur-gear 34, (see Fig. 3,) which gear meshes with a smaller gear 35, mounted upon a short standard 36, said gear 35 having connected thereto a band-pulley 37, to which motion is transmitted by a band 38, passing about the pulley 12 on the wheel-shaft 5. Provision is thus made for imparting motion to the shaft 33, which constantly maintains a uniform relation to that of the wheel-shaft. The gear 31 on sleeve 32 is provided with an annularly-grooved hub which receives the forked end of a reversing-lever 39, pivoted upon a vertical stud 40 on the table 16, the long arm of which extends to the front side of the machine and terminates in a suitable handle, as shown. (See Figs. 1, 5, and 6.) By grasping said handle and swinging the lever the sleeve 32 can be moved to throw either of its gears into action and thus reverse the direction of movement of the work-carriage; but I provide means whereby such reversal of movement is secured automatically, which are as follows:

To the side of the work-carriage are adjustably secured two tappets 41 42 by means of screws passing through slots therein, (see Fig. 6,) and to the edge of table 16 is pivotally hung an elbow-lever 43, (see Figs. 6, 16, and 17,) the long arm of which lever stands in the path of the tappet 42 as the work-carriage nears the end of its movement in one direction. The short arm of said lever enters a notch in a vertically-disposed pin 44, mounted in a housing 45, secured to the table, and a coil-spring 46, surrounding said pin within the housing, exerts an upward pressure on the pin to cause its upper end to enter a recess in the under side of the reversing-lever, thereby retaining the latter in the position shown in Fig. 5, with the bevel-gear 31 in operative engagement with gear 29. A coil-spring 47 (see Fig. 5) is connected at one end to the table and at its opposite end to lever 39, near its front end, said spring thereby tending to move said lever toward the left or in a direction to disengage the gear 31 from gear 29 and move gear 30 into engagement with the latter. Piv-

totally mounted upon the table is a short lever 48, the short arm of which lies in the path of tappet 41 on the carriage as the latter nears the end of its movement toward the front side 5 of the machine, and the long arm of which engages the side of lever 39, (see Fig. 5,) a light spring 49 keeping said lever in such position. Said lever 48 is of such length that its action upon lever 39 will be sufficient to 10 disengage gear 30 from gear 29, but will not move gear 31 into engagement with the latter, the carriage being thus brought to a rest to permit the insertion of a new blade in the work-holder, after which it is again set in motion 15 by manually shifting the lever to throw gear 31 into engagement with gear 29. The parts being in the position shown in Fig. 5, the continued movement of the carriage toward the rear side of the machine will cause 20 its tappet 42 to swing lever 43 and depress pin 44 to release the reversing-lever, whereupon the spring 47 throws the latter to its opposite position and reverses the movement of the carriage. When the carriage nears the 25 end of its movement in the opposite direction, its tappet 41 engages lever 48 and gradually moves it and the reversing-lever until the carriage comes to a rest. The adjustability of the tappets renders it possible to vary the extent 30 of the traverse to correspond with work of different lengths.

The work-carriage is provided at its edge adjacent to the abrading-wheel with the two bearings 50, which receive the trunnions 51, 35 projecting from the opposite ends of the die-holder 52, (shown detached in Fig. 19,) whereby said die-holder is rendered free to rock upon said trunnions, and the means provided for imparting a positive rocking movement 40 thereto are preferably as follows: A shaft 53, supported in bearings 54 on table 16, (see Fig. 5,) carries at one end a spur-gear 55, which meshes with gear 24, and upon said shaft is mounted an eccentric 56, (see Fig. 11,) which 45 has a spline-and-groove connection with the shaft to permit movement thereof longitudinally of the latter. The die-holder 52 is provided at one end with a laterally-projecting arm composed of the two members 57 58, (see 50 Figs. 10, 11, and 12,) which are connected together, by the hinge-joint 59. The member 58 terminates at its outer end in a fork which embraces the eccentric 56, and two cap-pieces 59, applied to the sides of said fork, form a 55 housing for said eccentric and compel it to move longitudinally of shaft 53 with the work-carriage. The member 57 of said arm has its outer end provided with teeth formed on the arc of a circle of which the hinge-joint 60 59 is the center, and the member 58 is provided with a shoulder facing said teeth, in which is located a segment of a tapped hole to receive the adjusting-screw 60, which engages both the thread of said hole and the 65 teeth on the member 57, whereby an adjustment of one member upon the other can be

effected by turning said screw to vary the extent of the rocking movement imparted to the die-holder by the eccentric. A set-screw 61, passing through an arc slot in the member 57 into the member 58, serves to securely fasten said members together in any of their adjusted positions. Such rocking movement of the die-holder is for the purpose of securing the slight convexity transversely of the 75 blade with which knife-blades are finished, and the described means for adjusting the amount of such movement adapts the machine for producing the proper convexity on blades of varying widths as well as for varying the degree of convexity on blades of the same width.

In its side adjacent to the abrading-wheel the die-holder 52 is provided with a recess to receive the die-plate 62, (see Figs. 19 and 20,) 80 which is secured thereto by screws, as shown, or in any convenient manner. Said die-plate has its acting face provided with a shoulder or rest 63 for supporting the blade and conforming substantially to the shape of the edge of 85 the latter, as shown in Fig. 20, and is preferably provided with the vertical channels 64 in its wall above said rest, as shown, which obviate the necessity of reducing the entire face of said wall to a true plane, and thereby lessen the cost 90 of manufacture of the die-plate and also serve to permit a portion of the water fed to the wheel during the grinding operation to escape behind the blade and prevent the latter from being unduly heated. A series of such die-plates will be used interchangeably to correspond with blades of varying sizes and shapes. Referring to Figs. 5, 13, 14, and 15, the preferred means for clamping the blade upon 95 said die-plate are as follows: At its front end 100 the die-holder 52 is provided with the laterally-projecting hub 65, through which extends a squared hole to receive the stem 66 of a clamping-jaw 67, the acting face of which opposes the face of the die-plate and is slightly 105 tapered to correspond with the taper of a knife-blade at the butt-end of the latter, at which point said jaw engages a blade placed on said plate. The stem 66 is made square 110 for a short distance from the jaw, whereby it 115 is prevented from turning within the hole in the die-holder, and is made round from such point to its outer end, where it is threaded to receive a nut 68 and a lock-nut 69. A collar 70 on said stem is formed with a shoulder 120 to abut against the end of the hub 65 and projects for a short distance into the bore of the latter, where it is securely held from movement by a set-screw 71. A coil-spring 72, surrounding the stem between said collar 125 and the squared portion of the former, presses the stem in a direction to move the jaw 67 away from the face of the die-plate. The outer end of said collar 70 forms a scroll-cam, (see Fig. 14,) and a lever 73 has its hub 74, which 130 embraces the stem between said collar and the nut 68, provided with a similar cam for

mation on its end adjacent to said hub, whereby the combined action of said cam-surfaces when the lever is moved about the stem as a center in one direction is to force the stem in a direction to carry the jaw 67 against the butt of a knife-blade laid against the die-plate and securely clamp it in such position. The collar 70 is provided with spanner-holes, as shown, and by loosening screw 71 and im-
 10 parting a partial rotation to said collar any wear between the two cam-surfaces can be taken up and the jaw can be caused to securely hold blades of varying thickness upon the die-plate. The position occupied by a
 15 knife-blade when clamped upon the die-plate is indicated by broken lines in Figs. 7 and 19. I also provide means for automatically caus-
 ing the abrading-wheel to follow the beveled surface at the point of the blade to the ex-
 20 treme point of the latter, which are as follows: By reference to Figs. 8 and 21 it will be ob-
 served that the way 20, upon which the work-
 25 carriage 21 moves, is provided in its outer side and near its front end with a shallow re-
 cess 75, and that the carriage makes its con-
 tact with the way at that side by means of two screw-pins 76, which are locked in any posi-
 30 tion of adjustment by means of lock-nuts
 77. In its opposite side the carriage is pro-
 35 vided with a series of holes in which are lo-
 cated coil-springs 78, surrounding pins 79,
 screwed into said holes, which springs bear
 40 against the adjacent side of the way 20, there-
 by drawing the ends of the pins 76 against
 45 the opposite side of the way with sufficient
 force to cause one of said pins, when it reaches
 50 said recess 75 as the carriage approaches the
 end of its forward movement, to enter said
 55 recess and thereby impart to the carriage a
 60 slight tilting movement horizontally, such
 movement being allowed by the swivel con-
 65 nection of the nut 23 with the carriage, as here-
 inbefore mentioned. The recess 75 is so lo-
 70 cated and is of such conformation that such
 75 tilting movement of the carriage will cause
 75 the beveled surface at the point of the knife-
 80 blade to bear against the face of the abrad-
 85 ing-wheel to the extreme point of the blade.
 As shown in said Figs. 8 and 21, the recess
 90 75, instead of being made in the wall of the
 95 way itself, is made in a thin bar of steel 83,
 set into a recess in the way and secured in
 100 place by screws, such construction enabling
 105 said bar to be hardened to increase its wear-
 110 ing quality and also enabling different bars
 115 with different sizes and shapes of recesses to
 120 suit knife-blades of different sizes and shapes
 125 to be used interchangeably. In Figs. 22 and
 130 23 I have shown the recess 75 as being located
 135 in a block 76, which is dovetailed into the
 140 way, and in Figs. 24, 25, and 26 I have shown
 145 it as being located in a short bar 77, movably
 150 inserted within a groove in the way, said bar
 155 having its end bent at a right angle to receive
 160 an adjusting-screw 78, by means of which
 165 said bar can be adjusted to vary the position

of the recess to suit different styles and sizes of blades. In either of said forms the bar or plate containing the recess acts as a former to properly finish the blade at its pointed end. 70

A rotary pump 79 (see Figs. 3 and 4) is mounted at the rear side of the machine for withdrawing the water from the reservoir in the base and feeding it to the abrading-wheels through suitably-disposed pipes (not shown) 75 in a well-known manner, said pump being driven by a belt 80, connecting a pulley 81 on the pump-shaft with a pulley 82 on shaft 33.

As hereinbefore stated, the mechanism above described for holding and presenting 80 the work to the abrading-wheel at one end of the machine is duplicated at the opposite end in connection with the opposite wheel, thereby enabling two blades to be operated upon simultaneously, and the operation of the machine 85 is as follows: The work-carriages 21 being at the end of their traverse toward the front side of the machine, two knife-blades are applied to the die-plates thereon and clamped thereon by turning the levers 73. The operator then grasps the two levers 39 and moves them sufficiently to throw the gears 31 into engagement with gear 29, said levers being retained in such position by the entrance of the pins 44 into the recess in their under side. 90 The carriages are thus caused to move toward the rear side of the machine, carrying the knife-blades transversely across the faces of the annular abrading-wheels, while at the same time the rocking motion imparted to 95 the die-holders by the eccentrics 56 secure the desired convexity transversely to the blades. Such action continues until the tappets 42 on the carriages engage the levers 43 and by rocking the latter withdraw the pins 44 from 100 the reversing-levers, whereupon the springs 47 actuate said levers to throw the gears 30 into engagement with gears 29 and the carriages begin their return movement. Such movement continues until the tappets 41 en- 105 gage the levers 48 and actuate the reversing- 110 levers to withdraw the gears 30 from gears 29 and the carriages come to a rest. The operator then removes the blades and transposes them upon the die-plates and the operation is 115 repeated, the grinding being performed upon the opposite side of said blades. As before described, the slight tilting movement given to the carriages just before they come to rest at the front side of the machine by the de- 120 pressions 75 secure the desired bevel at the point of the blades. Such operation can go on indefinitely, the only changes in the machine required being the substitution of different die-plates for the varying sizes and 125 styles of blades and the adjustment of the tables 16 and the plates 26, as before described, should such adjustment become necessary to compensate for the wearing away of the face of the abrading-wheels. 130

It will be apparent that the machine operating as thus described has a capacity

for very rapid work, as well as for grinding blades with entire uniformity upon both sides thereof.

It will be obvious that the novel means devised by me for holding and presenting the blade to the abrading-wheel can be used in the manner herein described in connection with a single abrading-wheel, instead of being duplicated for use with two wheels, with-out departure from the scope of my invention.

Having thus fully described my invention, what I claim, and desire to secure by Letters Patent, is—

1. In a grinding-machine, the combination with an annular abrading-wheel, of a way extending parallel with the acting face of said wheel and having in one side thereof, near one of its ends, a depression or recess, a work-carriage mounted upon said way and having means for clamping thereon the work to be ground, said carriage being provided with inwardly-projecting engaging means near each end which bear against the recessed side of said way and with a spring or springs bearing against the opposite side of said way, and means, as a screw-shaft, for moving said carriage upon said way, substantially as set forth.

2. In a grinding-machine, an annular grinding-wheel, a work-carriage movable in a plane parallel with the acting face of said wheel, a work-holder pivotally supported upon said carriage, a screw-shaft operatively connected with said carriage for imparting a back-and-forth movement thereto, means substantially as described for imparting a rocking movement to said work-holder during the traverse of said carriage, and means for causing a slight tilting movement to the carriage in a horizontal plane as it approaches the end of its movement in one direction, combined and operating substantially as and for the purpose set forth.

3. In a grinding-machine, the combination with an annular abrading-wheel 7, of the table 16 mounted upon way 15, carriage 21 mounted upon the way 20 on said table, screw-shaft 22 supported in bearings upon said table, said shaft engaging a nut on said carriage and carrying the gear 24 at one end thereof, gears 25 29 mounted upon plate 27 adjustably secured to the bed of the machine, and screw-rod 18 operatively engaging said table for adjusting the same upon said way 15, substantially as described.

4. In a grinding-machine, the combination with an abrading-wheel, as 7, of a work-carriage 21 carrying the adjustable tappets 41 42, reversing-lever 39 operatively connected to the driving-work of said carriage for reversing its movement, spring-actuated pin 44 adapted to enter a recess in said lever to retain it in one position, lever 43 operatively

engaging said pin and having one arm thereof lying in the path of said tappet 42 on the carriage, lever 48 having one arm thereof in engagement with said lever 39 and its other arm lying in the path of said tappet 41, and spring 47, arranged and operating substantially as set forth.

5. In a grinding-machine, the combination with an abrading-wheel, as 7, of the work-carriage 21, screw-shaft 22 for operating the same, work-holder 52 pivotally supported upon said carriage, shaft 53 carrying the sliding eccentric 56, and an intermediate connection between said eccentric and said work-holder whereby the latter receives a rocking movement from the former, substantially as and for the purpose described.

6. In a grinding-machine, the combination with the carriage 21 and its operating screw-shaft 22, of shaft 53 having mounted thereon the sliding eccentric 56, work-holder 52 pivotally hung upon said carriage and provided with the laterally-extending arm composed of the members 57 58 united by the hinge-joint 59, said member 58 terminating in a fork which embraces said eccentric 56, and means, as the adjusting-screw 60, for adjusting one of said members upon the other to vary the rocking movement of said work-holder, substantially as set forth.

7. In a grinding-machine, the combination with the way 20 having in one side thereof the recess 75, of the work-carriage 21 provided with the pins 76 which bear against the recessed side of said way and with the springs 78 which bear against the opposite side of said way, substantially as and for the purpose set forth.

8. In a grinding-machine, the combination with the way 20 having secured to one side thereof a removable plate or bar, as 83, containing the recess 75, of the carriage 21 provided with the pins 76 and springs 78 as described, and the screw-shaft 22 engaging the swiveled nut 23 on said carriage, substantially as described.

9. In a grinding-machine, the combination with the shaft 5 carrying the wheels 7 and band-pulley 10, of the shaft 33 driven by intermediate band and gearing from said shaft 5 and carrying the splined sleeves 32 upon which are mounted the bevel-gears 30 31, reversing-levers 39 for shifting said sleeves, work-carriages 21 carrying the rocking work-holders 52, screw-shafts 22 carrying the gears 24, and the gears 29 25 for transmitting motion from said gears 30 31 to said gears 24, arranged and operating substantially as set forth.

WILBUR C. LAMBERT.
